ACOUSTIC HORN

Vincent Salmon, Chicago, Ill., assignor to Jensen
 Radio Manufacturing Company, Chicago, Ill.,
 a corporation of Nevada

Application July 23, 1942, Serial No. 452,112

17 Claims. (Cl. 181—27)

This invention relates to acoustic devices and in particular to acoustic horns of the type used with sound radiators or receivers, or used as a means for coupling acoustic conduits of different sizes or having different terminal impedances.

The ultimate objective of this invention is a sound reproducer or radiator, such as a radio loudspeaker, or a sound receiving device, such as a radio microphone, having high electroacoustic conversion efficiency which is uniform over a wide range of frequencies, the novel contribution toward the achievement of this objective being a horn, or, rather, a family of horns whose acoustic impedance characteristics are adjustable over a wide range. The great flexibility of this family of horns permits a closer approach to the attainment of optimum terminal impedance conditions under a wider variety of circumstances than has heretofore been possible.

The invention is more specifically directed to the improvement of the efficiencies of the acoustic devices mentioned above in the lower frequency ranges.

Subsidiary objects of the invention include the provision of a horn whose throat resistance rises at a predetermined rate with increasing frequencies immediately above the cut-off frequency and whose throat reactance characteristics can be adjusted within wide practical limits to annul over a part of the low frequency range the negative reactance of the associated mechanical or acoustical driving devices, including their associated electrical signal sources, in order that high power factor conditions may obtain.

An outstanding and most useful feature of the invention resides in the ability of a properly selected member of the horn family to achieve an ultimate throat resistance value with increasing frequency immediately above cut-off much more rapidly than the so-called exponential horn.

Although the horn herein described may be employed as an acoustic transducer in any type of application, it is principally used as an element of a horn loudspeaker to couple the vibrating diaphragm of the driving motor with the atmosphere as the sound transmitting medium. Accordingly, the description will proceed with this particular application as an example.

The horn is illustrated and certain of its characteristics are indicated in the accompanying drawings, in which

Fig. 1 is a side elevational view of a sound radiator or receiver, the horn being shown in

longitudinal section and following the contours defined by the within equation where $T=0.6$;

Fig. 6 contains profiles of horns, for comparison purposes, for three values of the parameter T of the horn equation given herein;

Fig. 3 is a chart indicating resistance characteristics of the horn for five values of the parameter;

Fig. 4 is a chart showing the experimentally determined relative efficiency-frequency characteristics of an exponential horn and of the horn of the invention where the equation parameter, T , is 0.6, both horns having the same cut-off frequencies and mouth areas;

Fig. 5 is a diagrammatic view in longitudinal section of a horn of the re-entrant type embodying the invention.

The contribution of the horn to the radiating efficiency of a horn loudspeaker depends, not merely upon the structure of the horn considered as a separate element, but also upon the relationship of the mechanical impedance looking toward the diaphragm of the driving motor with its associated electrical signal source, referred to herein as the driver impedance, to the mechanical impedance at the throat of the horn looking toward its mouth, this latter value being referred to herein as the horn throat impedance. The ideal arrangement from the standpoint of radiating efficiency of the loudspeaker would be one in which the acoustic loading of the driver diaphragm furnished by the horn is such that the driver impedance and the horn throat impedance are conjugate; that is, the resistances are equal while the reactances are equal in magnitude and opposite in sign. This condition can be readily obtained with simple acoustical elements at a single frequency but can only be approached in actual practice over a range of frequencies for the reason that both the driver impedance and that of the horn throat vary independently over the useful frequency range. Since the greatest changes, especially in horn characteristics, occur in the lower frequency ranges, it is in this region that horn design exerts greatest influence on the overall response of the speaker unit.

Considering, first, the nature of the driver impedance which must be matched by the horn, it may be stated that the resistance component of this impedance is approximately constant over the low frequency range. It follows that for high and uniform overall efficiency the horn throat resistance should be as nearly constant as possible and equal to the resistance component

of the driver impedance. Of the several types of horns heretofore known to the art, the exponential type most nearly approaches this requirement. As will be shown hereinafter, the present invention encompasses horns which meet this requirement to a substantially greater extent.

While resistance considerations are generally determinative of the particular horn structure to be used with a given driving motor, the reactance component of the driver and horn throat impedances is generally a factor to be considered and may, in certain circumstances, be controlling. Where the cut-off frequency of the horn (the frequency below which the acoustic resistance of the horn is zero) is below the resonant frequency of the driving motor with the impedance on the horn side of the diaphragm reduced to zero, it is possible to substantially match and annul the reactance of the driver, which, in this range, is 10 capacitative, by means of a properly selected member of the horn family herein described. The throat reactance of such a horn will be positive and its average value will decrease with increasing frequency. With the correct resistance 15 characteristic this reactance annulling results in a system which approaches a conjugate match of impedances with consequently improved efficiency of power transfer to the atmosphere.

Fig. 1 of the drawings illustrates an acoustic device which may be taken to be either a loud-speaker comprising a horn 10, shown in section, and driving motor 11, or a sound receiving device in which case the element 11 would be a pressure sensitive acousto-electric transducer. In this simple form of horn the axis, which is represented by the broken line bearing the legend "axis," is a straight line. Considering the device here illustrated as a loudspeaker, sound generated by the vibrating diaphragm of the driving motor 11 enters the horn 10 at the throat 12, traveling through the horn and emerging into the atmosphere at the mouth 13 of the horn. The impedance characteristics of the acoustic load furnished to the diaphragm by the horn depends upon the interior configuration of the horn, or more specifically, the manner in which the cross-sectional area of the horn increases with distance from the throat. Whether the horn is of the simple, straight type, as illustrated in Fig. 1, or of the coiled, folded, or re-entrant type, or whether the cross-section is circular, rectangular, or of some other configuration, the axis of the horn is defined as the locus of points marking the mean or average of the acoustic path or channel provided by the horn. In the case of an annular passage, the mean path is a surface rather than a line. The cross-sectional area at any point within the horn is the area of a surface which is perpendicular to its axis or mean acoustic path and bounded by the walls of the horn. For example, the cross-sectional area of the horn at a distance, x , from the throat 12 is the area, S , of the plane indicated by the line so designated in Fig. 1. The smallest area of the horn is that of the throat, S_t , and the largest area is that of the mouth.

In accordance with the invention, the cross-sectional area of horn 10 increases from a value, S_t , at the throat in accordance with the following definition:

$$S = S_t \left(\cosh \frac{x}{x_0} + T \sinh \frac{x}{x_0} \right)^2$$

In this equation,

S =cross-sectional area at distance x from the throat of the horn measured along mean acoustic path thereof,

$$\cosh \frac{x}{x_0}$$

is the hyperbolic cosine function of the argument

$$\frac{x}{x_0}$$

$$\sinh \frac{x}{x_0}$$

is the hyperbolic sine function of the argument

$$\frac{x}{x_0}$$

$$x_0 = \frac{c}{2\pi f_0}$$

c being the velocity of a plane sound wave in unbounded atmosphere and f_0 the cut-off frequency of the horn,

and T is a constant, a parameter which determines the character of the flare of a given horn. The family of horns embraced by this invention falls within the outer limits established by values of T equal to zero and infinity. A self-consistent set of units must, of course, be used in calculations, involving the equation. As used herein, the expressions, "positive finite value" and "positive value" shall be taken to include zero.

Although the claims specifically define the scope of the invention, in order to avoid any misconception it is pointed out here that when the parameter, T , is assigned a value of unity, the horn equation given above reduces to a function which defines the well known exponential horn, and when the value of T is infinite, the relationship reduces to a function which defines a conical horn which is also known in the art. These special members of the family are expressly disclaimed from the scope of the invention herein claimed.

The horn defined by the above equation when T is assigned a value of zero is the special case which results in a slope of zero at its throat with respect to its axis. In this case the horn equation reduces to the form

$$S = S_t \left(\cosh \frac{x}{x_0} \right)^2$$

When designing a horn for a particular application, many factors must be taken into consideration. The art is well aware of the bearing of such considerations as throat and mouth sizes and shapes, the materials of which the horn is constructed and the thickness of the walls. In proceeding with the specification of a horn in accordance with the present invention, it is first necessary to arrive at a tentative determination of the value of the parameter T . This selection

depends upon the characteristics which the complete loudspeaker is to possess and upon the impedance characteristics of the driving motor. Knowing these, the response of different members of the horn family (that is, for different values to T) may be predetermined. The curves of Fig. 3 show the relationship between acoustic resistance at the throat of the horn and the frequency of the sound input. They show that an ultimate value is approached by all members of the horn family in the higher frequency range. For the

reasons stated above, these curves may also be used to predict the relative acoustic output of the several horns of the family. Accordingly, if high efficiency immediately above cut-off is desired with uniformity over the broadest possible range, a value of T less than 1, say 0.6, is selected. If constancy of response over a wide range of frequencies is the desired objective, a value of T greater than 1 is to be chosen.

Having selected a value for T , the cut-off frequency f_0 is chosen. This will be near the lowest frequency to be reproduced by the loudspeaker and its exact value will depend upon engineering and economic factors. Then the throat area, S_t , may be determined from a consideration of the impedance characteristics of the driving motor. This is a process which, while somewhat complicated, is well understood by those skilled in the art. In a particular example, when the horn is to be used in association with a driving unit having a diaphragm area of four square inches and an unloaded resonant frequency of about 200 cycles per second, the value of S_t would be approximately 1.7 square inches.

With values assigned to T , f_0 , and S_t , the cross-sectional area of the horn at any point, x , may be determined from the law given above. The length of the horn, or, to put the limitation in terms of the controlling dimension, the area of the horn mouth depends upon the fidelity of reproduction to be achieved. The larger the area of the horn mouth, the better it radiates low frequency sounds. The ideal horn is of infinite length and mouth area. However, it is generally recognized that reflections of the sound wave emerging at the horn mouth are negligible, when the horn is used with a properly designed driving motor, where, in the case of the circular horn, the mouth area is such that its circumference is greater than the wave length of the sound of lowest frequency to be transmitted. Where the horn mouth is, or approximates, the shape of a regular polygon, this limitation may be stated in terms of an equivalent circular horn mouth, that is, the mouth of a hypothetical circular horn having the same area. With certain adjustments in the driving system, this limiting horn mouth circumference may be reduced by 50% without causing objectionable acoustic interferences. The nature of these adjustments, and, in general, the considerations which determine the mouth area of a given horn are known to those skilled in the art.

The profiles of several members of the family of horns and a comparison of the flare of the horns with that of the exponential horn are shown in Fig. 2. The three horns here diagrammatically illustrated have identical throat and mouth areas. The exponential horn 14 falls between the horn 15 which approaches the conical shape and the horn 16. It will be seen that horns following the equation given above for which the value of T is between zero and 1 have a smaller cross-sectional area at a given point on the axis than the exponential horn 14. This characteristic is of importance in curved or re-entrant horns, particularly in the higher frequency ranges, for the reason that the difference between the lengths of the extreme sound paths at the inside and the outside of the bent portions of the horn is less than, for example, that of the exponential horn. This means that interference effects at the bent portions of the sound passage are minimized.

Advantage is taken of this particular feature

of the invention in the horn illustrated in Fig. 5. In this double re-entrant horn, the sound generated by the driving motor 17 is transmitted by means of the acoustic conduit 18, which may provide either a circular or an annular sound passageway, to the annular intermediate section 19 of the horn and thence through the outer annular section 20 to the atmosphere. The differences in the inside and outside acoustic paths indicated by the arrows 21 and 22 at the bent portions 23 and 24 of the acoustic passageway depend upon the cross-sectional areas of the acoustic passageway or horn at these points.

Although the curves of Fig. 3 represent the throat resistance characteristics of infinite horns, they may also be taken to indicate a mean value or general trend of horns of finite length. These curves show that the rate of increase of throat resistance with increasing frequency immediately above the cut-off value increases with decreasing values of the parameter, T . These curves indicate that for the exponential horn ($T=1$) the throat resistance rises to the 10% tolerance zone on either side of ultimate throat resistance value at a frequency of 2.25 times the cut-off frequency. This point is reached at 1.3 times cut-off frequency when T is assigned a value of 0.707, the throat resistance remaining below the ultimate value throughout the entire frequency range. Again, the desired throat resistance range is reached at 1.1 times cut-off frequency when T is assigned a value of 0.6. In this case the resistance rises slightly above the ultimate value and gradually returns as the frequency increases. The two remaining curves of Fig. 3 show the throat resistance characteristics of other members of the horn family, indicating the wide range of characteristics obtainable which permits their adaptation to almost any type of driving unit.

The efficiency of a horn having a given mouth area and cut-off frequency and defined by the equation given herein where $T=0.6$ is shown in Fig. 4. The efficiency-frequency relationship of a corresponding exponential horn is also given for comparison purposes. Both of these curves represent experimentally determined values.

As hereinbefore stated, the general principles which apply to the use of a horn in a sound radiating device, such as a radio loudspeaker, are also operative when the horn is used with a sound receiving device or as a transformer between acoustic channels having different cross-sectional areas and therefore different terminal impedances. Thus, the invention herein described may be employed with a microphone or as a part of a sound ranging device. By choosing the proper value for the parameter, a horn of this invention may be used to selectively emphasize predetermined frequencies. The specification of a horn to be used with a sound receiver may be entirely different from one which is considered to be suitable when used with a loudspeaker since in the former case uniformity of response at the expense of maximum conversion efficiency may be desired. Values of T between 0 and 0.5 will provide selective pick-up of frequencies near cut-off with the usual acousto-electric generator; values of T near 0.6 produce a more uniform response over a wider band.

When used as a coupling transformer between two sections of an acoustic system, it is generally desirable that reflections from the coupling element be minimized in order that transmission through the line may be accomplished as efficiently as possible. Such an element is provided

in a horn whose parameter, T, is approximately 0.6 (0.55 to 0.65).

An outstanding advantage of the invention as it relates to the family as a whole is the great flexibility of the acoustic characteristics of the horns. The multitude of different conditions which occur with different types of equipment and for different applications may be met by means of the invention.

Slight deviations from the contours herein specified will, in most cases, result in only imperceptible effects. It must be recognized that fabrication of the horns by means of ordinary commercial equipment cannot follow the mathematical accuracy with which the horns are necessarily defined in the appended claims.

I claim:

1. An acoustic horn whose cross-sectional area increases from a value S_t at the throat of the horn substantially in accordance with the law

$$S = S_t \left(\cosh \frac{x}{x_0} + T \sinh \frac{x}{x_0} \right)^2$$

where

S =cross-sectional area at distance x from the throat of the horn measured along the mean acoustic path thereof

$$x_0 = \frac{c}{2\pi f_0}$$

c being the velocity of sound and f_0 the cut-off frequency of the horn

T is a constant having a positive finite value other than unity.

2. An acoustic horn whose cross-sectional area increases from a value S_t at the throat of the horn substantially in accordance with the law

$$S = S_t \left(\cosh \frac{x}{x_0} + T \sinh \frac{x}{x_0} \right)^2$$

where

S =cross-sectional area at distance x from the throat of the horn measured along the mean acoustic path thereof

$$x_0 = \frac{c}{2\pi f_0}$$

c being the velocity of sound and f_0 the cut-off frequency of the horn

T is a constant having a positive value of less than unity.

3. An acoustic horn whose cross-sectional area increases from a value S_t at the throat of the horn substantially in accordance with the law

$$S = S_t \left(\cosh \frac{x}{x_0} + T \sinh \frac{x}{x_0} \right)^2$$

where

S =cross-sectional area at distance x from the throat of the horn measured along the mean acoustic path thereof

$$x_0 = \frac{c}{2\pi f_0}$$

c being the velocity of sound and f_0 the cut-off frequency of the horn

T is a constant having a finite value greater than unity.

4. An acoustic horn whose cross-sectional area increases from a value S_t at the throat of the horn substantially in accordance with the law

$$S = S_t \left(\cosh \frac{x}{x_0} + T \sinh \frac{x}{x_0} \right)^2$$

where

S =cross-sectional area at distance x from the throat of the horn measured along the mean acoustic path thereof

$$x_0 = \frac{c}{2\pi f_0}$$

c being the velocity of sound and f_0 the cut-off frequency of the horn

T is a constant having a value of approximately 0.6.

5. An acoustic horn whose cross-sectional area increases from a value S_t at the throat of the horn substantially in accordance with the law

$$S = S_t \left(\cosh \frac{x}{x_0} \right)^2$$

where

S =cross-sectional area at distance x from the throat of the horn measured along the mean acoustic path thereof

$$x_0 = \frac{c}{2\pi f_0}$$

c being the velocity of sound and f_0 the cut-off frequency of the horn

6. An acoustic horn whose cross-sectional area increases from a value S_t at the throat of the horn substantially in accordance with the law

$$S = S_t \left(\cosh \frac{x}{x_0} + T \sinh \frac{x}{x_0} \right)^2$$

where

S =cross-sectional area at distance x from the throat of the horn measured along the mean acoustic path thereof

$$x_0 = \frac{c}{2\pi f_0}$$

c being the velocity of sound and f_0 the cut-off frequency of the horn

the value of T being such that predetermined horn throat resistance characteristics are obtained.

7. An acoustic horn whose cross-sectional area increases from a value S_t at the throat of the horn substantially in accordance with the law

$$S = S_t \left(\cosh \frac{x}{x_0} + T \sinh \frac{x}{x_0} \right)^2$$

where

S =cross-sectional area at distance x from the throat of the horn measured along the mean acoustic path thereof

$$x_0 = \frac{c}{2\pi f_0}$$

c being the velocity of sound and f_0 the cut-off frequency of the horn

the value of T being that which results in a horn throat resistance which deviates less than ten per cent from ultimate value over a maximum frequency range.

8. An acoustic horn whose cross-sectional area increases from a value S_t at the throat of the horn substantially in accordance with the law

$$S = S_t \left(\cosh \frac{x}{x_0} + T \sinh \frac{x}{x_0} \right)^2$$

where

S=cross-sectional area at distance x from the throat of the horn measured along the mean acoustic path thereof

$$x_0 = \frac{c}{2\pi f_0}$$

c being the velocity of sound and f_0 the cut-off frequency of the horn

T is a constant having a positive value of less than unity,

the acoustic resistance of said horn deviating less than ten per cent from ultimate value at all audible frequencies greater than twice cut-off frequency.

9. An acoustic horn in accordance with claim 1 and having a mouth whose area is greater than that of an equivalent circular horn mouth having a circumference equal to the length of the sound wave at cut-off frequency.

10. An acoustic horn in accordance with claim 1 and having a mouth whose area is greater than that of an equivalent circular horn mouth having a circumference equal to one-half the length of the sound wave at cut-off frequency.

11. In an electroacoustic sound reproducing device including an electrical signal source and electromechanical driving unit having an established mechanical impedance, an acoustic conduit whose cross-sectional area increases from a value S_t at the throat of the horn substantially in accordance with the law

$$S = S_t \left(\cosh \frac{x}{x_0} + T \sinh \frac{x}{x_0} \right)^2$$

where

S=cross-sectional area at distance x from the throat of the horn measured along the mean acoustic path thereof

$$x_0 = \frac{c}{2\pi f_0}$$

c being the velocity of sound and f_0 the cut-off frequency of the horn,

the values of S_t and of the parameter T being such that the throat impedance of said horn is substantially the conjugate of the mechanical impedance of said electrical signal source and driving unit over the frequency range from 1.5 to 5 times cut-off frequency.

12. In an electroacoustic sound reproducing device including an electrical signal source and an electromechanical driving unit having established mechanical reactance characteristics an acoustic horn coupled to said driving unit and comprising an acoustic conduit whose cross-sectional area increases from a value S_t at the throat of the horn substantially in accordance with the law

$$S = S_t \left(\cosh \frac{x}{x_0} + T \sinh \frac{x}{x_0} \right)^2$$

where

S=cross-sectional area at distance x from the throat of the horn measured along the mean acoustic path thereof

$$x_0 = \frac{c}{2\pi f_0}$$

c being the velocity of sound and f_0 the cut-off frequency of the horn,

the values of S_t and of the parameter T being such that the throat reactance of said horn is equal in magnitude and opposite in sign to the mechanical reactance of said electrical signal source and driving unit over the frequency range from 1.5 to 5 times cut-off frequency.

13. In an acousto-electric sound receiving device including a sound sensitive acousto-electric transducer, an acoustic horn coupled to said transducer whose cross-sectional area increases from a value S_t at the throat of the horn substantially in accordance with the law

$$S = S_t \left(\cosh \frac{x}{x_0} + T \sinh \frac{x}{x_0} \right)^2$$

where

S=cross-sectional area at distance x from the throat of the horn measured along the mean acoustic path thereof

$$x_0 = \frac{c}{2\pi f_0}$$

c being the velocity of sound and f_0 the cut-off frequency of the horn

T is a constant having a positive value less than 0.5

14. In an acoustic system including acoustic conduits of different cross-sectional areas, an acoustic connector comprising a conduit whose terminal cross-sectional areas are equal to the cross-sectional areas of the respective acoustic conduits connected thereby, the cross-sectional area of said connector increasing from a value S_t at the small end thereof substantially in accordance with the law

$$S = S_t \left(\cosh \frac{x}{x_0} + T \sinh \frac{x}{x_0} \right)^2$$

where

S=cross-sectional area at distance x from the small end of the connector measured along the mean acoustic path thereof

$$x_0 = \frac{c}{2\pi f_0}$$

c being the velocity of sound and f_0 the cut-off frequency of the connector

T is a constant having a value of approximately 0.6.

15. An acoustic horn of the re-entrant type comprising a retroverted acoustic conduit whose cross-sectional area increases from a value S_t at the throat of the horn substantially in accordance with the law

$$S = S_t \left(\cosh \frac{x}{x_0} + T \sinh \frac{x}{x_0} \right)^2$$

where

S=cross-sectional area at distance x from the throat of the horn measured along the mean acoustic path thereof

$$x_0 = \frac{c}{2\pi f_0}$$

c being the velocity of sound and f_0 the cut-off frequency of the horn

T is a constant having a positive value between zero and unity.

16. The acoustic horn of claim 13 where the

acoustic passageway within said conduit at a bent portion thereof is annular in cross-section.

17. An acoustic horn of the re-entrant type comprising a retroverted acoustic conduit whose cross-sectional area increases from a value S_0 at the throat of the horn substantially in accordance with the law

$$S = S_0 \left(\cosh \frac{x}{x_0} \right)^2$$

where

S =cross-sectional area at distance x from the throat of the horn measured along the mean acoustic path thereof

5

$$x_0 = \frac{c}{2\pi f_0}$$

c being the velocity of sound and f_0 the cut-off frequency of the horn.

VINCENT SALMON.
